VAPOR GENERATOR

John Blizzard, Garden City, N. Y., assignor to
 Foster Wheeler Corporation, New York, N. Y., a
 corporation of New York

Application November 4, 1941, Serial No. 417,754

8 Claims. (Cl. 122—479)

This invention relates to vapor generators and particularly pertains to a method of, and apparatus for, controlling the degree of superheat of vapors in vapor generators.

The invention provides a method of, and means for, readily and easily regulating the degree of superheat of the vapor to meet different operating requirements, or for maintaining the degree of superheat constant over a wide range of generator loads or ratings.

In accordance with the invention, a steam generator, for example, is arranged so that the superheater and the burners for firing the furnace thereof are so positioned relative to each other that the superheater will receive a greater amount of radiant heat from the firing of one burner or group of burners than it will receive from the firing of another burner or group of burners. This is accomplished by placing the superheater in a recess in the furnace wall so that it is shielded more or less from the radiant heat of certain burners, but is exposed to direct radiation from the flames of other burners, or the superheater elements may be inclined at such an angle as to receive a greater amount of radiant heat from some burners than from others. Additionally, refractory material may be placed on certain of the heat absorbing elements of the generator in such a manner that the radiant heat received directly by the superheater from the flames of certain burners will be augmented by the re-radiation to the superheater of heat received by this refractory material from the burners.

With these arrangements, the temperature to which the steam is superheated may be controlled by differentially firing the burners or burner groups; or by increasing the supply of fuel to certain burners and decreasing it to other burners, or the temperature of the steam may be regulated by changing the ratio of the amount of air to fuel in those burners to the flame of which the superheater is directly exposed.

The invention will be understood from the following description when considered in connection with the accompanying drawing forming a part thereof, and in which:

Fig. 1 is a more or less diagrammatic vertical sectional view of a steam generator embodying the invention, and

Fig. 2 is a partial vertical sectional view of one of the furnace walls showing one means for increasing the radiant heat to a superheater.

Referring to the drawing, the steam generator illustrated comprises a setting 10 having a furnace chamber 11 fired by fuel burners 12 and 13

disposed in front wall 14 of the setting, to direct a stream of gases of combustion toward the rear of the chamber. The groups of burners 12 and 13 are vertically spaced from each other, and the burners of each group are horizontally spaced.

The furnace chamber is provided with a hopper bottom formed by oppositely inclined side wall portions 15 and 16. The upper portion of the furnace chamber is defined by vertical side walls 17 and 18. Between the lower end of the side walls and the upper end of the hopper walls are wall portions 19 and 20 which are vertically inclined oppositely to the hopper walls 15 and 16 respectively. In the upper portion of the setting are upper steam and water drums 21 and 22. The drum 21 is connected to a lower drum 23 by a vertical bank of steam generating tubes 24, and the drum 22 is connected to the lower drum 23 by a vertically inclined bank of tubes 27 which extend transversely of the chamber 11. Gases flow from the setting through a flue passage 26.

Extending between the two upper drums are horizontal groups 28 and 29 of circulator tubes. Disposed in the space bounded by the group of circulator tubes 29, vertically inclined bank 27 and vertical bank 24, is a convection superheater 30 which is in the path of the gases flowing from the furnace to the flue passage 26. Saturated steam is conducted from drum 21 through line 31 to the superheater inlet header 32 and after flowing through the superheater, it is conducted from the outlet header 33 by a line 34.

The inner surfaces of the furnace walls 17 and 18 are lined respectively with water wall tubes 35 and 36. At their upper ends the water wall tubes 35 are connected to the drum 23 and at their lower ends to a header 37. The water wall tubes 36 are connected at their upper ends to the drum 22 and at their lower ends to a header 38. These tubes are connected with the circulatory system of the unit in any desired manner. The inner surface of the walls 15 and 16 of the hopper bottom are lined respectively with water wall tubes 39 and 40. The water wall tubes 39 are connected at their lower ends to a header 41 and at their upper ends to a header 42, while the tubes 40 are connected at their upper ends to a header 43 and at their lower ends to a header 44. The tubes 39 and 40 are connected to the circulatory system of the generator by suitable downcomer connections, not shown, in any desirable manner so that they will be cooled by the circulation of water therethrough. The tubes 39 and 40 may also be used as superheaters in which event they would be connected as hereinafter described.

Lining the inner surfaces of the furnace wall portions 19 and 20 are radiant heat absorbing superheater tubes 46 and 47 respectively. The tubes 46 are connected to inlet and outlet headers 48 and 49 respectively, while the tubes 47 are connected to inlet and outlet headers 50 and 51. As shown, saturated steam passes from the drum 21 through the conduit 31 to the convection superheater 30. From the convection superheater the steam may be passed to either the superheater 46 or the superheater 47. For example, the steam may be passed from the convection superheater 30 through the line 34 to the radiant superheater 47 through the inlet header 50 thence from the outlet header 51 to the inlet header 48 for the radiant heat absorbing superheater tubes 46 so that the final temperature of the superheated steam will be a result of the combined heating effect of both the convection and the radiant superheaters. Obviously, steam from the convection superheater 30 could be passed into the radiant superheater 46 thence into the radiant superheater 47. With the arrangement of the present invention, the superheater tubes 46 and 47 are directly exposed to radiant heat from the fuel burners 12 but substantially shielded from direct radiations from the flames produced by the burners 13.

In operation, gases of combustion flow from the furnace chamber 11 over the bank of tubes 27, the convection superheater 30 and the bank of steam generating tubes 24 into the flue passage 26. Steam from the drum 21 is conducted to and through the convection superheater and then flows to and through the radiant superheaters 47 and 46. If a high degree of superheat is required, the burners 12 and 13 are operated. The superheater tubes 46 and 47 are exposed directly to the radiant heat of the flame from the burners 12, but due to their position in the setting, are only indirectly exposed to the radiant heat of the flame from burners 13.

If a low degree of superheat is required, burners 13 only are operated, or, one or more of these burners are operated, depending upon the degree of superheat required. When these burners only are used, the superheater tubes 46 and 47 are only indirectly exposed to the radiant heat of these burners, in consequence of which the steam flowing therethrough is not heated to as high a degree as when the burners 12 are operated.

It will be perceived therefore that the intensity of firing of the different burners or burner groups, or the number of burners of each group in operation, may be varied to obtain any desired degree of superheat at any load on the generator. The ratio of air and fuel supplied to the various burners also may be adjusted to regulate the temperature of the steam. In the form shown, however, tubes 46 and 47 will receive a higher degree of heat under various firing conditions from the burners 12 than from the burners 13.

In the embodiment of the invention shown in Fig. 2, at least part of the tubes 39 and 40 are covered with refractory material 45 which material is capable of radiating heat. When the tubes 39 and 40, or a part thereof, are covered with a refractory material, heat from the burners 12 and 13 is re-radiated from the material to the tubes 46 and 47, thereby increasing the radiant heat received by these tubes. Due to the proximity of the burners 12 to the refractory surfaces, the maximum quantity of heat will be re-radiated

from these surfaces to the tubes 46 and 47 when the burners 12 are operated.

Although the invention is disclosed as embodied in a vapor generator having a combination convection and radiant superheater, it is also applicable to any vapor generator having a single superheater so disposed in the furnace chamber that in operation it will be more directly exposed to radiations from one burner or group of burners than from the radiations of another burner or group of burners. It is obvious that the convection superheater 30 may be omitted and one or both of the radiant superheaters only may be utilized. Obviously, the manner of connection of the superheaters to one another is a matter of choice.

If desired, the water wall tubes 39 and 40 on the inner surface of the walls 15 and 16 respectively of the hopper bottom may be replaced by superheater tubes. When superheater tubes are so used, the steam preferably is passed from the steam drum 21 or from the convection superheater, serially through the tubes 40, 47, 39 and 46, so that the final temperature of the superheated steam will be dependent upon the combined heating effect of these tubes.

Although a preferred embodiment of the invention is disclosed herein, changes may be made in the particular form and relative arrangement of the various parts of the apparatus described without departing from the principles of the invention which is not to be limited excepting by the scope of the appended claims.

What is claimed is:

1. A vapor generator comprising a setting having opposite side and end walls, vapor generating tubes in the setting, a furnace chamber within said walls and having portions offset therefrom in opposite side walls thereof, said offset portions each having a vertically inclined wall, a radiant superheater in each of said offset portions adjacent and substantially parallel to the inclined wall thereof, means for firing said furnace comprising burners in one end wall of said setting adapted to direct a stream of gases of combustion toward the other end wall, at least one of said burners being so disposed that heat from the gases of combustion thereof is radiated directly into the offset portions, and another burner so positioned that the radiant superheaters are substantially shielded from radiations from the gases of combustion thereof.

2. A steam generator comprising a setting having opposite side and end walls, steam generating tubes in the setting, a furnace chamber within said walls, a hopper bottom associated with the furnace comprising opposite walls inclined inwardly, side wall portions inclined oppositely to said hopper bottom walls and extending between the upper portion of the hopper bottom walls and the lower portion of the first-mentioned side walls, radiant superheaters extending along the opposite hopper walls and the said side wall portions, separately controlled burners in one end wall of the setting adapted to direct a stream of gases of combustion toward the opposite end wall, at least one of said burners being so disposed that heat from the gases of combustion thereof is radiated directly to the radiant superheaters, and another burner so positioned that the radiant heat superheaters are substantially shielded from radiations from the gases of combustion thereof.

3. A steam generator comprising a setting having opposite side and end walls, steam generating tubes in the setting, a furnace chamber with-

in said walls, a water cooled hopper bottom associated with the furnace comprising opposite walls inclined inwardly, refractory material covering at least a part of said walls, side wall portions inclined oppositely to said hopper bottom walls and extending between the upper portion of the hopper bottom walls and the lower portion of the first-mentioned side walls, radiant superheaters extending along the said side wall portions, separately controlled burners in one end wall of the setting adapted to direct a stream of gases of combustion toward the opposite end wall, at least one of said burners being so disposed that heat from the gases of combustion thereof is radiated directly to the radiant superheaters, and another burner so positioned that the radiant superheaters are substantially shielded from radiations from the gases of combustion thereof.

4. A steam generator comprising a setting having opposite side and end walls, a furnace chamber within said walls having a portion offset therefrom in the lower portion thereof, upper steam and water drums positioned at opposite sides of said chamber at the upper end thereof, a lower drum, a substantially vertical bank of steam generator tubes between the lower drum and one of the upper drums, a vertically inclined bank of tubes extending from the lower drum transversely of the chamber to the other upper drum, tubes extending between the two upper drums, a flue passage through which gases of combustion pass after flowing through said vertical bank of tubes, a radiant superheater in the offset portion of said furnace adapted to receive steam from the steam generating tubes, a burner for firing the furnace chamber so disposed that heat from the gases of combustion thereof is radiated directly into the offset portion, and another burner so positioned that the radiant superheater is substantially shielded from the radiations of the gases of combustion thereof.

5. A steam generator comprising a setting having opposite side and end walls, steam generating tubes in the setting, a furnace chamber within said walls, a hopper bottom associated with the furnace comprising opposite walls inclined inwardly, side wall portions inclined oppositely to said hopper bottom walls and extending between the upper portion of the hopper bottom walls and the lower portion of the first-mentioned side walls, radiant superheaters extending along the said side wall portions, separately controlled burners in one end wall of the setting adapted to direct a stream of gases of combustion toward the opposite end wall, at least one of said burners being so disposed that heat from the gases of combustion thereof is radiated directly to the radiant superheaters, and another burner so positioned that the radiant superheaters are substantially shielded from radiations from the gases of combustion thereof.

6. A vapor generator comprising a setting, vapor generating tubes in the setting, a furnace

chamber having a gas outlet adjacent the upper portion thereof, said chamber having a laterally offset portion therein with a vertically inclined wall, a radiant superheater in said offset portion adjacent and substantially parallel to the inclined wall thereof, a burner for firing the furnace chamber so disposed that heat from the gases of combustion thereof is radiated directly into the offset portion, and another burner positioned at a higher elevation than the first mentioned burner and at a lower elevation than said outlet, said other burner being disposed to fire in such a direction that the gases in flowing to the outlet will not descend a substantial distance below the burner and so that the radiant superheater will be substantially shielded from the radiation from the gases of combustion thereof.

7. A vapor generator comprising a setting having opposite side and end walls, one of said side walls having a portion extending outwardly thereof in a vertically inclined direction, vapor generating tubes in the setting, a furnace chamber within said walls, a radiant superheater disposed adjacent and substantially parallel to said outwardly extending portion of the side wall, means for firing said furnace comprising burners in one end wall of said setting adapted to direct a stream of gases of combustion toward the other end wall, at least one of said burners being so disposed that heat from the gases of combustion thereof is radiated directly to the radiant superheater, and another burner positioned at a higher elevation than the first mentioned burner and at a lower elevation than said outlet, said other burner being disposed to fire in such a direction that the gases in flowing to the outlet will not descend a substantial distance below the burner and so that the radiant superheater will be substantially shielded from the radiation from the gases of combustion thereof.

8. A vapor generator comprising a setting, vapor generating tubes in the setting, a furnace chamber having a gas outlet adjacent the upper portion thereof, said chamber having a laterally offset portion therein with a wall vertically inclined outwardly from the chamber, a radiant superheater in said offset portion adjacent and substantially parallel to the inclined wall thereof, a hopper bottom associated with the furnace comprising opposite walls inclined outwardly toward the chamber, a burner for firing the furnace chamber so disposed that heat from the gases of combustion thereof is radiated directly into the offset portion, and another burner positioned at a higher elevation than the first mentioned burner and at a lower elevation than said outlet, said other burner being disposed to fire in such a direction that the gases in flowing to the outlet will not descend a substantial distance below the burner and so that the radiant superheater will be substantially shielded from the radiation from the gases of combustion thereof.
